United States Patent

Des. 238,681

Patented Feb. 3, 1976

238,681

COMPUTER CONSOLE OR SIMILAR ARTICLE

Edward K. Driscoll, Marlboro, and John F. Graham,
Sudbury, Mass., assignors to Honeywell Information
Systems Inc., Waltham, Mass.

Filed Mar. 22, 1974, Ser. No. 453,909

Term of patent 14 years

Int. Cl. D14—02

U.S. Cl. D26—5 C

FIG. 1

FIG. 2

FIG. 3

FIG. 4

FIG. 1 is a front perspective view of a computer console showing our new design;

FIG. 2 is a front elevational view thereof;

FIG. 3 is a side elevational view thereof;

FIG. 4 is a top plan view thereof.

The rear of the computer console, not shown, is substantially plain and unornamented.

What is claimed is:

The ornamental design for a computer console or similar article, substantially as shown and described.
